US00D689502S

(12) **United States Design Patent**
Belitz et al.

(10) **Patent No.:** **US D689,502 S**
(45) **Date of Patent:** **** Sep. 10, 2013**

(54) **DEVICE SUPPORT APPARATUS**

(71) Applicant: **Swift Distribution, Inc.**, Torrance, CA (US)

(72) Inventors: **Michael Belitz**, Manhattan Beach, CA (US); **Patrick M. Bertsch**, Thornton, CO (US)

(73) Assignee: **Swift Distribution, Inc.**, Torrance, CA (US)

(**) Term: **14 Years**

(21) Appl. No.: **29/443,598**

(22) Filed: **Jan. 18, 2013**

(51) LOC (9) Cl. **08-07**

(52) U.S. Cl.

USPC **D14/447**

(58) Field of Classification Search

USPC D14/432, 433, 434, 439, 440, 451, D14/452, 239, 217, 224.1, 251, 252, 253, D14/457, 458, 459, 460, 461; D6/406.1, D6/406.2, 406.3, 406.4, 406.5, 406.6; 361/679.06, 679.21, 679.22, 679.24, 679.26, 361/679.27, 679.28, 679.3, 679.55, 679.56, 361/709; 248/917-924, 133, 136, 139, 150, 248/176.1, 188.6; D12/415

(57) **CLAIM**

The ornamental design for a device support apparatus, as shown and described.

DESCRIPTION

FIG. 1 is a front view of a device support apparatus showing our new design;

FIG. 2 is a rear view thereof;

FIG. 3 is a top view thereof;

FIG. 4 is a bottom view thereof;

FIG. 5 is a right view thereof;

FIG. 6 is a left view thereof;

FIG. 7 is a perspective view thereof;

FIG. 8 is a front view thereof, but showing the leg (kickstand) in an alternate position for storage;

FIG. 9 is a rear view thereof;

FIG. 10 is a top view thereof;

FIG. 11 is a bottom view thereof;

FIG. 12 is a right view thereof;

FIG. 13 is a left view thereof; and,

FIG. 14 is a perspective view thereof.

1 Claim, 14 Drawing Sheets
